UNITED STATES PATENT OFFICE.

JAMES M. CALKINS, OF PEORIA, ILLINOIS, ASSIGNOR TO SCOTT HEAD LAMP CONTROL, OF MIAMI, FLORIDA, A CORPORATION OF FLORIDA.

DIRIGIBLE HEADLIGHT FOR AUTOMOBILES.

Application filed January 19, 1925. Serial No. 3,381.

My invention relates to improvements in dirigible headlights for automobiles, and it consists in the combinations, constructions, and arrangements herein described and 5 claimed.

An object of my invention is to provide a dirigible headlight constructed for automobiles which has novel means for moving the reflectors in the headlights, so as to 10 direct the rays from the headlights in the same direction in which the wheels are turned.

A further object of my invention is to provide a device of the type described in 15 which novel means is provided for varying the swing of the reflectors with respect to the front wheels of the automobile, this means also being adapted to permit the wheels to move without swinging the reflectors.

A further object of my invention is to provide a device of the type described in 20 which all of the moving parts are concealed, whereby the moving parts are protected from foreign matter such as dust, dirt, and 25 the like.

Other objects and advantages will appear in the following specification, and the novel features of the invention will be particularly 30 pointed out in the appended claims.

My invention is illustrated in the accompanying drawings, forming part of this 35 application, in which—

Figure 1 is a front elevation of the device, 40 Figure 2 is a section along the line 2—2 of Figure 1,

Figure 3 is a section along the line 3—3 of Figure 2,

Figure 4 is a sectional view showing the 45 mechanism for varying the swing of the reflectors with respect to the front wheels of the vehicle,

Figure 5 is a section along the line 5—5 of Figure 4, and

Figure 6 is a section along the line 6—6 of Figure 4.

In carrying out my invention I make use 50 of an automobile which has the usual front fenders 1. A headlight supporting mechanism comprising a pipe 2 and headlights 3 is secured to the fenders 1 by means of brackets 4. Figure 4 shows how the pipe 2 is formed in two sections, these sections being secured to each other by means of a 55 casting 5. The casting 5 also houses the

mechanism for swinging the reflectors in the headlights 3, and for varying the swing of the reflectors.

In Figures 2 and 3 I show the way the reflectors 6 are mounted in the headlights 3. 60 It will be noted from these figures that the reflectors 6 are pivotally secured to rings 7 at 8. The rings in turn are pivotally mounted in the headlights 3 at 9. Figure 2 shows how the ring 7 is adapted to be 65 rotated by means of a rod 10. The rod 10 is secured to the ring 7 at one of its ends and has its lower end provided with a gear 11. Figure 4 shows how the rods 10 with their gears 11 are operatively connected to 70 each other and to the reflector swinging mechanism. A rack 12 has slots 13 therein through which the rods 10 extend. One side of the slots 13 has teeth 14 that are adapted to mesh with the teeth in the gears 75 11. It will be seen from this construction that when the rack 12 is moved in the pipe 2, it will cause the rods to rotate so as to swing the reflectors in a horizontal plane.

In addition to the horizontal swing of the 80 reflectors, the reflectors are tilted forwardly when swung. A cam 15 is rigidly secured to each of the reflectors 6 and has a cam slot 16 therein into which the free end of a pin 17 is slidably disposed. The pin is 85 carried by the casing of the reflector 3, and it will therefore be apparent that when the reflector 6 is swung by the ring 7, the pin 17 will also cause the reflector to tilt downwardly. In this way the reflectors are not 90 only moved with the wheels but are also tilted forwardly so as to direct the light down upon the road.

The means for moving the rack 12 comprises a rack 18 that is adapted to rotate a 95 gear 19 (see Figure 5) when the rack 18 is moved. The gear 19 is mounted on a shaft 20 that in turn carries a gear 21. The gear 21 is disposed in a slot 22 that is similar to the slots 13. The slot 22 is provided with 100 teeth 23 that are in mesh with the gear 21. When the rack 18 is moved, it will rotate the gears 19 and 21 so as to move the rack 12. I found it convenient to dispose the casting 5 adjacent to the radiator 24 so as to 105 permit an actuating rod 25 to pass through the shell of the radiator and to extend up to the steering rod 27. The rod 25 is connected to the steering rod by any means such as a crank arm 26. When the rod 27 is 110

turned, it will move the rod 25 so as to move. It often happens, however, cause the rod to slide back and forth in the casting 5. The rod 25 is connected to a lever 28 by means of a pin 29. The lever 28 is provided with a slot 30 in which a pin 31 is slidably disposed. Figure 6 clearly shows how the pin 31 passes through the slot 30 and also how the pin is slidably disposed in slots 32 in the casting 5. A frame 33 is provided for moving the pin 31 for a purpose hereinafter described. The frame 33 has arms with openings through which the pin 31 extends.

The frame 33 is adapted to be moved by means of a knurled nut 34 or the like. The nut 34 is mounted upon a threaded shank 35 of the frame 33. The nut 34 is rotatably carried by the casting 5 by means of a ring 36. It will be seen from this construction that when the nut 34 is rotated it will move the frame 33, the frame in turn moving the pin 31 in the slots 30 and 32. The casting 5 has grooves 37 which act as guideways for the frame 33.

When the pin 31 is in the position shown in Figure 4 the rod 25 swings the lever 28 so as to move the rack 18. It will be noted in Figure 4 that the rack 18 has a rounded end portion 38 that slidably contacts with the free end of the lever 28. The rack 18 is spring pressed by means of springs 39, and these springs are adapted to yieldingly hold the portion 38 in contact with the lever 28. The dotted lines in Figure 4 show the lever 28 in two positions and also show how the springs 39 keep the rack 18 in contact with the lever 28. The lever 28 imparts a maximum movement to the rack 18 when the pin is in the position shown in Figure 4. If now the nut 34 is rotated so as to move the pin 31 toward the opposite end of the slot 30, the lever 28 will impart a less movement to the rack 18. If the pin 31 is moved over to the opposite end of the slot 30 from that in which it is shown it will permit the lever 28 to pivot thereon without imparting any movement at all to the rack 18. This construction provides a simple mechanism for connecting the rack 18 to the rod 25 at all times and for also changing the relative movements of the rack 18 with respect to the rod 25, this change being accomplished at the will of the operator. Furthermore, if the operator so desires, he may move the pin 31 so as to permit the rod 25 to move without moving the rack 18. In this way the reflectors 6 are retained in a fixed position even though the wheels of the car are being turned by the driver.

From the foregoing description of the various parts of the device, the operation thereof may be readily understood. The reflectors 6 are normally connected to the rod 25 so as to be swung when the rod is turned, it will move the rod 25 so as to move. It often happens, however, cause the rod to slide back and forth in the casting 5. The rod 25 is connected to a lever 28 by means of a pin 29. The lever 28 is provided with a slot 30 in which a pin 31 is slidably disposed. Figure 6 clearly shows how the pin 31 passes through the slot 30 and also how the pin is slidably disposed in slots 32 in the casting 5. A frame 33 is provided for moving the pin 31 for a purpose hereinafter described. The frame 33 has arms with openings through which the pin 31 extends.

The frame 33 is adapted to be moved by means of a knurled nut 34 or the like. The nut 34 is mounted upon a threaded shank 35 of the frame 33. The nut 34 is rotatably carried by the casting 5 by means of a ring 36. It will be seen from this construction that when the nut 34 is rotated it will move the frame 33, the frame in turn moving the pin 31 in the slots 30 and 32. The casting 5 has grooves 37 which act as guideways for the frame 33.

When the pin 31 is in the position shown in Figure 4 the rod 25 swings the lever 28 so as to move the rack 18. It will be noted in Figure 4 that the rack 18 has a rounded end portion 38 that slidably contacts with the free end of the lever 28. The rack 18 is spring pressed by means of springs 39, and these springs are adapted to yieldingly hold the portion 38 in contact with the lever 28. The dotted lines in Figure 4 show the lever 28 in two positions and also show how the springs 39 keep the rack 18 in contact with the lever 28. The lever 28 imparts a maximum movement to the rack 18 when the pin is in the position shown in Figure 4. If now the nut 34 is rotated so as to move the pin 31 toward the opposite end of the slot 30, the lever 28 will impart a less movement to the rack 18. If the pin 31 is moved over to the opposite end of the slot 30 from that in which it is shown it will permit the lever 28 to pivot thereon without imparting any movement at all to the rack 18. This construction provides a simple mechanism for connecting the rack 18 to the rod 25 at all times and for also changing the relative movements of the rack 18 with respect to the rod 25, this change being accomplished at the will of the operator. Furthermore, if the operator so desires, he may move the pin 31 so as to permit the rod 25 to move without moving the rack 18. In this way the reflectors 6 are retained in a fixed position even though the wheels of the car are being turned by the driver.

From the foregoing description of the various parts of the device, the operation thereof may be readily understood. The reflectors 6 are normally connected to the rod 25 so as to be swung when the rod is turned, it will move the rod 25 so as to move. It often happens, however, cause the rod to slide back and forth in the casting 5. The rod 25 is connected to a lever 28 by means of a pin 29. The lever 28 is provided with a slot 30 in which a pin 31 is slidably disposed. Figure 6 clearly shows how the pin 31 passes through the slot 30 and also how the pin is slidably disposed in slots 32 in the casting 5. A frame 33 is provided for moving the pin 31 for a purpose hereinafter described. The frame 33 has arms with openings through which the pin 31 extends.

I claim:

1. In a dirigible headlight construction for vehicles, a headlight casing, a reflector movably mounted in said casing, means for swinging said reflector in a horizontal plane and for swinging said reflector forwardly when swung in a horizontal plane, said means being actuated by the steering mechanism of the vehicle, and means for automatically varying the swing of the reflector, said means being adapted to connect and disconnect the reflector from the steering mechanism.

2. The combination with a vehicle having a steering mechanism, of headlights carried by said vehicle, reflectors movably mounted in said headlights, means for automatically swinging said reflectors in a horizontal plane and for tilting the reflectors forwardly, and means connecting said reflector moving means with the steering mechanism of the vehicle, said means being adapted to connect and disconnect said reflector moving means with said steering mechanism.

3. The combination with a vehicle having a steering mechanism, of headlights carried by said vehicle, reflectors movably mounted in said headlights, means for automatically swinging said reflectors in a horizontal plane and for tilting the reflectors forwardly, and means connecting said reflector moving means with the steering mechanism of the vehicle, said means being adapted to connect and disconnect said reflector moving means with said steering mechanism, and for varying the swinging of said reflectors.

4. In a device of the type described, a reflector turning means including a slidable member, an actuating rod operatively connected to said slidable member, a lever for connecting said rod with said member, and means for changing the pivot point of said lever so as to vary the swing of said lever, whereby various movements may be imparted by said rod to said member.
  5. In a device of the type described, a reflector, a member operatively connected to
- said reflector so as to swing said reflector, a rod adapted to be moved by the steering mechanism of the vehicle, a lever operatively connecting said rod to said member, means for changing the pivot point of said lever so as to vary the movement imparted to said member by said rod, said means being adapted to move the pivot point of the lever so as to permit the rod to move without imparting a movement to said member.

JAMES M. CALKINS.
